UNITED STATES PATENT OFFICE.

ALFRED ISHERWOOD, OF NEW BEDFORD, MASSACHUSETTS.

LOOM-SHUTTLE.

1,156,404.

Specification of Letters Patent. Patented Oct. 12, 1915.

Application filed June 16, 1913. Serial No. 774,077.

To all whom it may concern:

Be it known that I, ALFRED ISHERWOOD, a citizen of the United States, and a resident of New Bedford, in the county of Bristol 5 and State of Massachusetts, have invented a new and useful Improvement in Loom-Shuttles, of which the following is a specification.

My invention relates to loom-shuttles of either the automatic or common type and its 10 object is to provide a simple and effective threading device as well as to improve the construction of the shuttle in the manner hereinafter set forth.

I shall describe my invention with reference to the drawings which accompany and 15 form a part of this specification, but it will be understood that various modifications may be made in the particular devices disclosed without departing from the spirit of 20 my invention.

In the drawings,—Figure 1 is a plan view of one embodiment of my invention. Fig. 2 is a section taken on the irregular line 2—2 of Fig. 1 and showing the threader and its 25 sheet metal extension in elevation. Fig. 3 is a section taken on the line 3—3 of Fig. 1. Figs. 4 and 5 are transverse sections taken on the lines 4—4 and 5—5, respectively, of Fig. 3. Fig. 6 is a side view of an element 30 which I term a bridge. Fig. 7 shows a blank from which the hook-plate may be bent. Fig. 7^a is a side view of an element which I call a protector plate. Fig. 8 shows a blank from which the threader and 35 its extension may be bent, when the threader and extension are integral. Fig. 9 is a transverse section corresponding to Fig. 4, and taken on the line 9—9 of Fig. 3 to show a modified form of bridge 22 which may be 40 substituted for the bridge 19 in Fig. 3. Fig. 10 is a blank from which the bridge shown in Fig. 9 may be bent. Fig. 11 is a plan view of the outer end of the shuttle showing a modified form of hook-plate. Fig. 12 is a 45 section taken on the line 12—12 of Fig. 11. Fig. 13 is a perspective view of the hook-plate shown in Fig. 11. Fig. 14 shows a blank from which the hook-plate illustrated in Fig. 13 may be bent. Fig. 15 shows a 50 blank from which another form of hook-plate may be bent. Fig. 16 is a transverse section corresponding to Fig. 12 and showing the modified hook-plate which is formed from the blank illustrated in Fig. 15. Fig. 55 17 is a perspective view of the hook-plate shown in Fig. 16. Fig. 18 is a transverse

section corresponding to Figs. 12 and 16 and illustrating a further modification of the hook-plate. Fig. 19 is a perspective view of the hook-plate shown in Fig. 18.

60

In the particular drawings selected for more fully disclosing my invention, 1 represents a shuttle having the usual cop-cavity 1' and 2 is a cop secured in said cavity in the usual manner. Slightly separated from the frontward wall of the shuttle is a plate 3, herein shown as formed of sheet-metal, having its upper edge 3' preferably inclined with respect to the front wall of the shuttle 65 at any desired angle, and shown in the present instance as being substantially flush with the top of the shuttle, although it will be understood that said upper edge may extend above the top of the shuttle and be bent over the front wall of the same. In order to 70 suitably space the plate 3 from the shuttle, the off-sets 3'' may be bent out from the blank as shown in Fig. 5. The inward end of the plate 3 may, as shown, be secured within the slot 4, and if desired, a pin 20 75 80 may be employed to hold said end in position. The threader proper comprises an upright portion 6 terminating in a stem 8, a substantially horizontal top portion 5 extending part way across the throat of the 85 shuttle and a down-turned substantially-vertical portion 7 having its inward end terminating in a spur 9 and its outward end in a finger 10 which projects slightly into the depression 10' cut into the wall of the shuttle. 90 The hook-plate 12 and the protector-plate 15 are secured to the stem 8 of the threader by a rivet which passes through the holes 17 in each of these members and the upper end of the protector-plate may be provided with 95 lugs 16 which fit into recesses 16' cut into the under side of the top portion 5 for the purpose of making a tight joint between said plate and top portion and thereby prevent 100 all danger of the thread being caught between the upper part of the hook-plate and the under side of the top portion 5. The stem formed by riveting the members 8, 12 and 15 together, is inserted in a slot in the shuttle and is held in position in any suitable 105 manner as by the pins 21 21 passing therethrough. The hook 13 which trends inwardly and frontwardly passes through the slot 11 in the upright portion 6 of the threader and projects slightly into the recess 13' in the wall of the shuttle. The outward 110 edges of the threader, the hook-plate and

the protector are stamped out to form the eye 14. The bridge 19 extends parallel to the down-turned portion 7 of the threader and is slightly separated therefrom as shown in Fig. 1. This bridge may be secured in position by driving the pins 19', formed integral therewith, into the floor of the shuttle, and is provided with a slot 19'' near one corner thereof so as to allow of a close adjustment of the spur 9 to the side of the bridge, as shown in Fig. 4, said spur being bent frontwardly toward said slot.

The operation is as follows: On the inward movement of the shuttle the thread is wound off the bobbin 2 and passes over the top portion 5 and the down-turned portion 7 of the threader, going into the space 33 between said down-turned portion and the rearward wall of the shuttle and under the finger 10. It then passes under the spur 9 and comes against the rearward wall of the bridge 19 and thence up and over said bridge and into the space 29 between the bridge and threader, being inclosed now by the three sides of the threader, the bridge and the floor of the shuttle between the bridge and protector-plate and running along the rearward wall of said protector-plate. On the outward movement of the shuttle the thread passes through the space 33' between the outward end of the top portion 5 of the threader and the wall of the shuttle, thence between the hook 13 and its coöperating recess 18' and into the eye 14, and thence into the space 34 between the plate 3 and the shuttle, and finally into the long space 32 between the plate 3 and the shuttle, its position now being as indicated by the dotted line A', Figs. 1 and 2. On the next inward pick, the thread passes through the space 32 and around the hook 13, assuming the position shown at A in full lines in Fig. 1.

It will be noted that the forward inclination of the upper edge 3' of the plate will prevent the filling-fork from sliding the yarn over the cop-cavity and entangling it with the yarn which is whirling off the bobbin when the shuttle is used in a right-hand loom. In fact the filling-fork does not cause the thread to leave the space 32, and the thread passes under the upper left-hand corner 32' of the plate 3, the position of the inward portion of the thread during the operation of the filling-fork being shown at A' in the left-hand end of Fig. 1. At the beginning of the inward pick when the thread is being drawn out of the space 32 and before it reaches the hook 13, the thread will fall to the front of the shuttle because of the forward inclination of the upper edge 3' of the plate 3 and will not get into the cop-cavity. On the outward pick, the stretch of free yarn is shorter than if the upper edge of the plate 3 were not inclined

toward the forward wall of the shuttle, for this stretch extends only from the corner 32' to the fork and not from the eye 14 to the fork as would be the case if said edge were not forwardly inclined.

It will be noted that that portion of the yarn which runs off the cop to the eye and that portion thereof which has the position A' on the outward pick are completely separated the one from the other by the plate 3 and therefore cannot come in contact with each other and break, and also that the yarn runs off the bobbin within, instead of outside, the shuttle and therefore cannot get cut or blackened. Another advantage of my invention is that a left-hand shuttle can be used in right-hand looms to get the same result as a right-hand shuttle in a right-hand loom, namely a short stretch of free filling from the selvage of the cloth to the shuttle.

In the modification shown in Fig. 9, the points 25 of the bridge are driven into the floor of the shuttle and the horizontal portion 23 now forms the floor of the space 90 along which the thread travels within the threader. The upright portion 22 of this modified bridge, which is provided with a slot 22'', has the same position as the corresponding part 19 of the bridge shown in Fig. 1, and the stem 24 is riveted to the stem 8 of the threader and the hook-plate 12. In this modification, the protector-plate 15 may be omitted, the upper end of the hook-plate forming a tight joint with the under side of the top portion 5 of the threader to prevent the thread from catching.

In the modification shown in Fig. 11, the hook-plate 27, besides having a hook 26, is provided with a laterally-extending guard 28, which extends over the bridge as shown, the purpose of this guard being more effectually to prevent ballooning or over-throwing. In this case as before, the hook-plate and protector, if the latter be employed, are riveted to the stem 8 of the threader.

The hook-plate 30 bent from the blank shown in Fig. 15, is provided with a hook 26 and carries another form of transverse guard 31 having a point 31' extending into the floor of the shuttle. If desired, a pin 35 of hardened steel or the like may be secured to the hook-plate 30 and hook 26 as shown in Figs. 16 and 17, for the purpose of affording a smooth surface for the yarn, especially silk or cotton yarn, to travel over on the inward movement of the shuttle. The particular advantage of the hook-plate shown in Figs. 15, 16 and 17, as well as that of Fig. 18 hereinafter described, is that the threader can be located farther forward than in the case of the other hook-plates, so as to bring the slot 33 in line with the axis of the spindle, and this results in the threader-blade requiring less offset,

so that the two threads may be kept farther apart at the threader-end when the thread is being drawn out of the space 32 on the outward movement of the shuttle. The thread 5 from the bobbin passes along the edge of the guard 31 and is thereby kept in line with the axis of the spindle, the point 31' extending into the floor of the shuttle to prevent the thread from getting under the 10 guard. This form of hook-plate is chiefly used in automatic shuttles, where it is desirable that the thread should pass in a straight line from the bobbin to the threader or the slot 33, to lessen the liability of 15 breakage when the shuttle is automatically threaded.

The hook-plate 36, shown in Figs. 18 and 19, is provided with a transverse guard 38 having a downwardly-extending point 38', 20 which, as shown in Fig. 18, is driven into the floor of the shuttle and performs the same function as the point 31' of the hook-plate shown in Fig. 16. The transverse guard 38 extends over the bridge 19 as in 25 the case of the guard 28 shown in Fig. 12.

It will be obvious that in Figs. 16 and 18 the guards 31 and 38 both keep the yarn practically in line with the axis of the bobbin, so that the yarn does not run along the 30 protector plate as in the case of Fig. 12, and that therefore these guards projecting across the path of the yarn put the latter under a certain amount of tension.

In order more clearly to define the directions of the various elements with respect to the shuttle, I have adopted the terms "frontward" and "rearward", as applied to the walls of the shuttle, and the term "inward" and "outward", as applied to the direction 35 of the shuttle in operation, in the same sense in which they have been used in the patent to Northrup 926,016, June 22, 1909. For example, the plate 3 is adjacent to the frontward wall of the shuttle and the downturned portion 7 of the threader lies toward the rearward wall, and the finger 10 trends toward the outward portion of the shuttle, and the spur 9 toward the inward part thereof.

50 I claim:

1. In a loom-shuttle having a threader and a cop-cavity, a plate secured to the threader and extending the length of the cop-cavity, whereby a space is provided between said plate and one wall of the shuttle to be traversed by the filling-thread when the shuttle is moving in one direction, the upper edge of said plate being inclined frontwardly.

60 2. In a loom-shuttle having a threader and a cop-cavity, a plate integral with the threader and extending the length of the cop-cavity, whereby a space is provided between said plate and one wall of the shuttle to be traversed by the filling-thread when

the shuttle is moving in one direction, the upper edge of said plate being inclined frontwardly.

3. In a loom-shuttle having a cop-cavity, a threader having a sheet-metal extension secured thereto and extending the length of the cop-cavity, and means spacing said extension from one wall of the shuttle, the upper edge of said extension being inclined frontwardly. 70

4. In a loom-shuttle having a threader and a cop-cavity, a plate secured to the threader and extending the length of the cop-cavity, whereby a space is provided between said plate and one wall of the shuttle to be traversed by the filling-thread when the shuttle is moving in one direction, the upper edge of said plate being inclined frontwardly and its inward end being secured in a groove in said shuttle. 80

5. In a loom-shuttle having a threader and a cop-cavity, a plate integral with the threader and extending the length of the cop-cavity, whereby a space is provided between said plate and one wall of the shuttle to be traversed by the filling-thread when the shuttle is moving in one direction, the upper edge of said plate being inclined frontwardly and its inward end being secured in a groove in said shuttle. 85

6. In a loom-shuttle having a cop-cavity, a threader having a sheet-metal extension secured thereto and extending the length of the cop-cavity, and means spacing said extension from one wall of the shuttle, the upper edge of said extension being inclined frontwardly and its inward end being secured in a groove in said shuttle. 90

7. In a loom-shuttle, a threader comprising an upright portion, a top portion terminating in a downturned portion, a finger extending outwardly and frontwardly from said downturned portion, said finger projecting into a recess in the shuttle, and a hook trending inwardly and frontwardly 105 and projecting from said upright portion into a depression in the wall of the shuttle. 110

8. In a loom-shuttle, a threader comprising an upright portion, a top portion terminating in a downturned portion, a finger extending outwardly and frontwardly from said downturned portion, said finger projecting into a recess in the shuttle, a hook trending inwardly and frontwardly and projecting from said upright portion into a 115 depression in the wall of the shuttle, and a bridge extending parallel to said downturned portion and spaced frontwardly therefrom.

9. In a loom-shuttle, a threader comprising an upright portion, a top portion terminating in a downturned portion, a finger extending outwardly and frontwardly from said downturned portion, said finger projecting into a recess in the shuttle, a hook 120 125

- trending inwardly and frontwardly and projecting from said upright portion into a depression in the wall of the shuttle, a bridge extending parallel to said downturned portion and spaced frontwardly therefrom, said bridge being provided with a slot, and a spur extending inwardly and frontwardly from said downturned portion and coöoperating with said slot.
10. In a loom-shuttle, a threader comprising an upright portion, a top portion terminating in a down-turned portion, a finger extending outwardly and frontwardly from said down-turned portion, said finger projecting into a recess in the shuttle, a hook trending inwardly and frontwardly and projecting from said upright portion into a depression in the wall of the shuttle, and a bridge extending parallel to said down-turned portion and spaced frontwardly therefrom, said bridge having integral pins driven into the floor of the shuttle.
11. In a loom-shuttle, a threader comprising an upright portion, a top portion terminating in a downturned portion, said upright portion ending in a stem sunk into a slot in the shuttle, and a hook-plate secured to said stem, said hook-plate having a hook passing through a slot in said upright portion and trending inwardly and frontwardly.
12. In a loom-shuttle, a threader comprising an upright portion, a top portion terminating in a downturned portion, said upright portion ending in a stem sunk into a slot in the shuttle and a hook-plate secured to said stem, said hook-plate having a hook passing through a slot in said upright portion and trending inwardly and frontwardly, and a guard extending transversely across the space between said upright and downturned portions.
13. In a loom-shuttle, a threader comprising an upright portion, a top portion terminating in a downturned portion, said upright portion ending in a stem sunk into a slot in the shuttle, a hook-plate secured to said stem, said hook-plate having a hook passing through a slot in said upright portion and trending inwardly and frontwardly, a guard extending transversely across the space between said upright and downturned portions, and a bridge secured to the floor of the shuttle and extending parallel to said downturned portion.
14. In a loom shuttle, a threader comprising an upright portion, a top portion terminating in a downturned portion, said upright portion ending in a stem sunk into a slot in the shuttle, a hook-plate having a hook passing through a slot in said upright portion and trending inwardly and frontwardly, and a protector-plate also secured to said upright portion and having lugs on its upper part entering recesses in the under side of said top-portion.
15. In a loom-shuttle, a threader comprising a stem, a hook-plate having a hook passing through a slot in said threader, and a protector-plate located on the rearward side of said hook-plate, said hook-plate and protector-plate being secured to said stem and sunk in a slot in said shuttle.
16. In a loom-shuttle having a threader and a cop-cavity, means for dividing said cop-cavity longitudinally into a compartment for the cop and a guide-groove for the thread, said means having its upper edge inclined frontwardly.
17. In a loom-shuttle, a threader having an extension located to divide the cop-cavity longitudinally into a compartment for the cop and a guide-groove for the thread, said extension having its upper edge inclined frontwardly.
18. In a loom-shuttle, a threader comprising an upright portion, a hook-plate having a hook passing through a slot in said upright portion, a guard extending transversely from said hook-plate, and a pointed-member integral with said guard and extending into the floor of the shuttle.
19. In a loom-shuttle, a threader comprising an upright portion, a hook-plate having a hook passing through a slot in said upright portion, a guard extending transversely from said hook-plate and having a vertical portion terminating in a point sunk into the floor of the shuttle, the rearward edge of said vertical portion being approximately in line with the axis of the bobbin.
20. In a loom-shuttle, a threader having an upright portion, a top portion terminating in a downturned portion, a bridge spaced frontwardly from said downturned portion, and a guard extending transversely across the space between said upright and downturned portions, the rearward edge of said guard being spaced frontwardly from said bridge.
21. In a loom-shuttle, a threader having an upright portion, a top portion terminating in a downturned portion, a bridge spaced frontwardly from said downturned portion, and a guard extending transversely across the space between said upright and downturned portions, the rearward edge of said guard being spaced frontwardly from said bridge and terminating in a pointed portion sunk into the floor of the shuttle.
22. In a loom-shuttle, a threader having an upright portion, a hook-plate having a hook trending inwardly and frontwardly, said hook projecting through a slot in said upright portion, and a horizontal pin passing between said hook and hook-plate so as to afford a smooth surface over which the filling thread will pass on the inward movement of the shuttle.
23. In a loom-shuttle having a threader and a cop-cavity, a plate secured to the

threader and extending the length of the cop-cavity, whereby a space is provided between said plate and one wall of the shuttle to be traversed by the filling-thread when 5 the shuttle is moving in one direction.

24. In a loom-shuttle having a threader and a cop-cavity, a plate integral with the threader and extending the length of the cop-cavity, whereby a space is provided between said plate and one wall of the shuttle 10 to be traversed by the filling-thread when the shuttle is moving in one direction.

25. In a loom-shuttle having a threader and a cop-cavity, means for dividing said

cop-cavity longitudinally into a compartment for the cop and a guide-groove for the 15 thread.

26. In a loom-shuttle, a threader having an extension located to divide the cop-cavity longitudinally into a compartment for the 20 cop and a guide-groove for the thread.

In testimony whereof, I have hereunto subscribed my name this 13th day of June, 1913.

ALFRED ISHERWOOD.
